UNITED STATES PATENT OFFICE.

FRANK TROWBRIDGE KENT, OF SYRACUSE, NEW YORK.

AUTOMATIC FEED-WATER REGULATOR FOR STEAM-BOILERS.

SPECIFICATION forming part of Letters Patent No. 443,577, dated December 30, 1890.

Application filed October 18, 1888. Serial No. 288,522. (No model.)

To all whom it may concern:

Be it known that I, FRANK TROWBRIDGE KENT, of the city of Syracuse, county of Onondaga, and State of New York, have invented 5 certain new and useful Improvements in Feed-Water Regulators for Steam-Boilers, of which the following is a specification.

My invention relates to improvements in automatic feed-water regulators for steam-boilers in which a float is located within a cylindrical steam-tight vessel or tank connected with the boiler above and below the high and low water points thereof by two pipes and having the steam-supply pipe for the passage 15 of steam to operate the steam-pump pass perpendicularly through the center of the bottom and top of said tank from bottom to top, and in construction with the parts hereinafter fully described is used to automatically 20 control the exit of steam from the boiler through the supply-pipe to the steam-pump, and thereby regulate the supply of feed-water to the boiler automatically.

The object of my invention is to so construct and combine the parts with the steam-supply pipe of the steam-pump between the boiler and steam-pump as shall produce a device which under every condition shall be reliable and efficient to automatically control 30 the supply and supply the boiler with feed-water.

With this end to attain my invention consists in passing the steam-supply pipe of the steam-pump perpendicularly through the center of the cylindrical float-vessel from the bottom to the top thereof and inserting a stop or plug in the supply-pipe at a point a little above the middle of the float-vessel and making holes or openings of equal size in opposite 35 sides of said supply-pipe above and below said plug within the float-vessel and above the high-water point of the boiler and cutting grooves around the circumference of the supply-pipe opposite and equal in width 40 to the diameter of the holes or openings in the sides of the supply-pipe, whereby the steam is diverted in its passage to the steam-pump through such opening, and thence through the holes or openings in a sleeve into a steam-chamber surrounding the sleeve and inclosing 45 the openings in the sleeve, from which

chamber through holes in the sleeve above said plug steam again enters the supply-pipe through the holes therein above the plug and operates the pump, the passage of steam into 55 and from the steam-chamber being controlled by the height of the water in the boiler through the agency of a float in the float-vessel connected to the sleeve, which slides easily up and down on the supply-pipe within the float-vessel.

My invention consists, furthermore, of a sleeve closely fitted to slide easily up and down on said supply-pipe within the tank or float-vessel, and provided with holes or openings in opposite sides thereof and the same distance apart and of the same size as the holes or openings in the steam-supply pipe, and also in providing a steam-chamber surrounding the sleeve and inclosing the openings therein, whereby the passage of steam through the supply-pipe to operate the steam-pump is automatically controlled by the height of water in the boiler through the agency of the float connected to said sleeve and located 75 within the float-vessel.

My invention consists, furthermore, of a float provided with an opening or tube in its center, which allows it to slide over the steam-supply pipe within the float-vessel, and also 80 having a collar closely fitted and securely fastened to the lower end of the sleeve in any suitable manner to form a tight joint in combination with the sleeve upon the supply-pipe, and the supply-pipe, when the float rests 85 upon the water, forms an air-tight chamber, which produces a suction in case the pressure of steam tends to lift the float from the water, and thereby the float performs a double office, in that it rides upon the water within 90 the tank and raises the sleeve up on the supply-pipe as the water rises in the boiler and by suction draws the sleeve down on the supply-pipe as the water in the boiler lowers, thereby causing the sleeve to be very sensitive 95 in its movements on the supply-pipe to the rise and fall of the water in the boiler, whereby, also, the passage of steam through the supply-pipe to the pump is automatically controlled. A collar is put upon the supply-pipe, so placed as to allow the sleeve to fall or slide down on the supply-pipe to a position 100

where the holes or openings in the supply-pipe and in the sleeve are opposite each other or opposite the circumferential grooves.

My invention consists in the detailed construction and arrangement of the parts, all as hereinafter more fully described, set forth, and pointed out.

Like letters in the drawings indicate corresponding parts in all the figures.

- 10 Figure 1 is an illustration of the invention, showing the connection of the boiler with the tank or float-vessel and the steam-pump. Fig. 2 is an enlarged representation of the invention with portions of each part cut away, so as to show the arrangement of the parts within the tank when the sleeve is dropped down and rests on the collar of the steam-supply pipe. Fig. 3 is an enlarged representation of a transverse vertical section of the various parts, illustrating their combination and adjustment with one another and the position they occupy when the sleeve is dropped down and rests upon the collar of the supply-pipe. Fig. 4 is an enlarged representation of the steam-supply pipe within the tank or float-vessel, showing its construction, the holes or openings in its sides, the circumferential grooves, and water-packing spaces. Fig. 5 is an enlarged sectional view 30 of the steam-supply pipe as constructed and represented in Fig. 4, showing the stop or plug and its location between the openings in the sides of the supply-pipe. Fig. 6 is an enlarged representation of a transverse vertical section 35 of the sleeve and the chamber surrounding it, showing the holes or openings in the opposite sides of the sleeve into the steam-chamber and also showing the steam-chamber. Fig. 7 is an enlarged representation of the 40 sleeve and casing surrounding and inclosing the steam-chamber. Fig. 8 is an enlarged cross-sectional view of the sleeve and steam-chamber surrounding it illustrated in Figs. 6 and 7, taken on line $x-x$ of Fig. 6. Fig. 9 is a vertical section of the float, showing the tube through its center and the collar to fit the sleeve. Fig. 10 is an enlarged representation of a transverse vertical section of the various parts, illustrating their combination and 50 adjustment with one another and the position they occupy when the sleeve is raised up on the supply-pipe and the passage of steam to the pump is cut off and the pump is at rest.

A represents the brick-work supporting and inclosing the boiler.

B represents the boiler, of ordinary construction.

V is the cylindrical steam-tight vessel or tank inclosing the float and sleeve.

60 S' is the pipe connecting the boiler above the high-water point with the float vessel or tank.

W is the pipe connecting the boiler below the low-water point with the float vessel or tank.

65 S is the steam-supply pipe, for passage of

steam to operate the steam-pump, connecting the boiler with the steam-pump, and a portion thereof passing perpendicularly through the center of the bottom and top of said float-vessel from bottom to top.

P is the steam-pump, of ordinary construction.

P' is the feed-pipe from the steam-pump to the boiler.

P² is a stop or plug permanently fixed in the steam-supply pipe.

O', O², O³, and O⁴ are the holes or openings in the opposite sides of the supply-pipe. G and G' are the circumferential grooves opposite said openings O', O², O³ and O⁴, and equal in width to the diameter of said openings. It will be noticed that in case the sleeve turns upon the supply-pipe so that the holes or openings in each are not opposite each other 85 when the sleeve rests on the collar C', the holes or openings in the sleeve are opposite the circumferential grooves G and G' and the passage of steam is unobstructed.

D is the sleeve, closely fitted to slide easily 90 up and down on the steam-supply pipe within the tank.

O and O⁵ are the openings in the sleeve on its opposite sides and of the same diameter and distance apart as the holes or openings 95 in the supply-pipe.

E is the casing surrounding and inclosing the steam-chamber C.

C is the steam-chamber.

C' is the collar fastened upon the steam- 100 supply pipe, so placed as to allow the sleeve to fall or slide down on the supply-pipe to a position where the holes or openings in the sleeve may come opposite the openings in the supply-pipe or opposite the circumferential 105 grooves.

F is the float, provided with the tube or opening T through its center, which allows it to slide over the steam-supply pipe.

T is the tube or opening through the center of the float, and in combination with the other parts of the device forms an air-tight chamber when the float rests on the water in the tank and produces a suction in case the pressure of the steam in its passage through 115 the chamber tends to lift the float from the water in the tank.

I is the collar of the float, fitted closely and fastened in any suitable manner to form a tight joint to the lower end of the sleeve D. 120

It will be noticed that the steam enters the steam-chamber C from opposite sides of the sleeve D, and that the openings for ingress and egress of the steam to and from the steam-chamber are equal in size, and the float being under steam-pressure, together with the suction of the air-chamber of the float upon the water, holds the sleeve in perfect equilibrium.

Having pointed out the various parts of my 130 invention, the operation thereof in combination is as follows: The water and steam in the

boiler freely enter the float-vessel through the pipes W and S', and the water stands at the same level therein as in the boiler. When the water in the boiler rises to a sufficient height, 5 the float rises and lifts or slides the sleeve upward on the steam-supply pipe, and the openings in the sleeve are raised above the openings in the supply-pipe, as shown in Fig. 10, and the steam-pump is at rest. As the 10 water is exhausted in the boiler, the float is gradually drawn down by gravity and the suction of the air-chamber in the float, and thereby the sleeve is drawn down on the steam-supply pipe to a position where the openings 15 O and O⁵ come opposite the openings O', O², O³, and O⁴ of the supply-pipe, respectively, or opposite the circumferential grooves, as shown best in Fig. 3, and the steam-pump is again set in motion by the passage of the steam from 20 the boiler through the steam-supply pipe S and the openings O', O², and O into the steam-chamber C, and from the steam-chamber through the openings O⁵ and O³ and O⁴ again into the supply-pipe to the pump, whereby 25 the boiler through the medium of the steam-pump is supplied with water. To lessen the friction of the supply-pipe and the sleeve and make the tube of the float air-tight when resting upon the water, the supply-pipe is 30 provided with water-packing spaces, as best shown in Fig. 4.

Having now fully and particularly described the nature of my invention and ascertained the object thereof and the manner in which 35 the same is to be performed and operated, I declare that what I claim as my invention, and desire to secure by Letters Patent, is—

1. An automatic feed water regulator for steam-boilers, comprising a float vessel or tank 40 connected to the boiler by pipes above and below the high and low water points of the boiler, a steam-pump for supplying the boiler with feed-water, having a steam-supply pipe for supplying steam to operate the steam-pump, 45 and connecting the boiler and steam-pump, a portion of said supply-pipe to pass perpendicularly from bottom to top through the center of the float-vessel, having said supply-pipe plugged at a point within the tank above the 50 high-water point of the boiler, and having holes or openings of equal size on opposite sides thereof within the float vessel or tank above and below said plug, and having circumferential grooves opposite said holes or 55 openings and in width equal to the diameter of said holes, having also a closely-fitted sleeve to slide easily up and down on said supply-pipe within the float-vessel, provided with holes or openings on opposite sides thereof 60 the same size and distance apart as the holes or openings in the steam-supply pipe, a steam-chamber surrounding said sleeve and inclosing the openings therein, and a float having a 65 tube through its center, passed over the supply-pipe within the float-vessel and fastened

to the lower end of the sleeve, substantially as and for the purposes set forth.

2. In a feed-water regulator, the combination of the float-vessel with the steam-supply pipe of the steam-pump by passing a portion 70 thereof perpendicularly through the center of the float-vessel from bottom to top and plugging said supply-pipe within the tank and providing it on opposite sides with steam-passages above and below the plug and above 75 the high-water point of the boiler, and also with circumferential grooves opposite and equal in width to the diameter of the steam-passages, having a sleeve closely fitted to move freely up and down on the supply-pipe 80 within the tank, said sleeve being provided with steam-passages on opposite sides and above and below said plug to allow at the same time an equal passage of steam from the supply-pipe below the plug into the steam-chamber surrounding the sleeve and from the steam-chamber into the supply-pipe above 85 the plug, controlled by the height of water in the boiler through the agency of a float attached to said sleeve, constructed and adjusted to one another substantially as and for the purposes set forth.

3. In a feed-water regulator, the combination of the sleeve D, closely fitted to move easily up and down on the supply-pipe, having the openings O and O⁵, the steam-chamber C, the supply-pipe S, having the openings O', O², O³, and O⁴, and the circumferential grooves G and G', said sleeve being constructed and connected to the float F so as to 95 be moved freely up and down on said supply-pipe within the tank through the medium of said float, constructed and combined substantially as represented, and for the purposes specified.

4. In a feed-water regulator, the sleeve D, with steam-passages O and O⁵ and steam-chamber C, adjusted to the steam-pipe S as represented and constructed, arranged, and operated relatively to each other so as to open 100 and close the passages O and O⁵ automatically by the height of the water in the boiler through the agency of the float F within the float-vessel V, as and for the purposes specified.

5. In a feed-water regulator, the combination of the float-vessel V with the supply-pipe S, passing perpendicularly through the center of the bottom and top of said float-vessel, said supply-pipe being constructed, substantially as represented, within the float-vessel and having the sleeve D closely fitted to the supply-pipe, with openings O and O⁵ and steam-chamber C, and moved freely up and down on the supply-pipe by the float F, automatically controlled by the height of the water in the boiler, as and for the purposes specified.

6. In a feed-water regulator, the combination of the sleeve D, having the openings O 130

and O⁵ and steam-chamber C, substantially as represented, with the float F, having the tube or opening T in its center to operate the sleeve upon the supply-pipe, substantially as 5 specified.

7. In a feed-water regulator, the combination of the float F, having the tube T through its center, and collar I, adjusted to the sleeve D and combined with the supply-pipe so as 10 to form an air-tight chamber when the float

rests upon the water within the float-vessel V, as and for the purposes specified.

In testimony whereof I have hereunto set my hand this 10th day of October, A. D. 1888, at Syracuse, New York, United States of 15 America.

FRANK TROWBRIDGE KENT.
